SMOKING PIPE

Frank Hodgekins Silverthorne, New York, N. Y.

Application September 12, 1931, Serial No. 562,437

13 Claims. (Cl. 131—12)

The invention relates to a sectional tobacco pipe in which smoke from the tobacco bowl is drawn into a smoke chamber and which is designed to have a drip receiving chamber for without drawing from the smoke chamber juices from the tobacco and any saliva which may drip through the pipe stem or mouth piece.

The primary object of the invention is to provide a smoking pipe of the type outlined which will afford a sweet, clean, dry smoke, free of odors or flavors which characterize known forms of such pipes. Incidental to this general object, the disclosure features the providing of a construction which will trap the juices drained from the smoke chamber and for disposing the juices in such way in a receptacle therefor that they cannot flow back into the pipe stem or into the tobacco bowl, even under those conditions where the pipe is laid on its side or inverted for the purpose of cleaning the tobacco bowl of a previously burned charge of tobacco.

Incidental to the desire to have a form of pipe which can be maintained cool, particularly in the stem or mouth piece element, the invention features the providing of means for minimizing heat transference from the hot tobacco-containing bowl to the stem or mouthpiece.

Another object of the invention is to provide a simplified form of sectional pipe of the type outlined, the parts of which can be readily demounted for cleaning.

Various other objects and advantages of the invention will be in part obvious from an inspection of the accompanying drawing and in part will be more fully set forth in the following particular description of one form of mechanism embodying my invention, and the invention also consists in certain new and novel features of construction and combination of parts hereinafter set forth and claimed.

In the accompanying drawing:

Fig. 1 is a view in vertical axial section through a preferred embodiment of the invention, and showing the pipe with its bowl or body portion in normal, operative smoking position, and

Fig. 2 is a transverse sectional view through the body portion, taken on the line 2—2 of Fig. 1 looking in the direction indicated by the arrow, and showing the pipe lying on its side.

In the drawing there is shown a holder 10, preferably made of wood, and including a tubular cylindrical body portion 11, internally threaded at opposite ends, as indicated at 12 and 13. The holder also includes as an integral part thereof a stem receiving tubular extension 14 projecting

from one side of the body portion 11. The outer portion of the bore of the tubular extension 14 is of cylindrical form as shown at 15, and the portion of the bore between the cylindrical portion 15 and the body portion 11 is of frusto-conical form as shown at 16, with the small end opening into the portion 11 between the threads 12 and 13.

A tobacco bowl 17, preferably formed of meerschaum or equivalent heat-resisting material, is intruded into the upper end of the body portion 11 with its side wall externally threaded at the central portion as shown at 18 and engaging the threads 12. The tobacco bowl projects above the top of the portion 11 and is provided at its upper end with an outlining flange 19 which engages the top of the portion 11 when the bowl 17 is screwed into position. The lower end of the tobacco bowl tapers downwardly in the form of a cone and at its lowest point is provided with a smoke and moisture discharging vent 20.

Positioned below the bowl 17 is a drain section 21 which includes an outlining ring 22, opposite ends of which are externally screw-threaded, as shown at 23 and 24, with an external flange 25 positioned between the threaded ends. The upper, threaded end of the ring 22 is screwed into the lower end of body portion 11, threads 13 engaging with threads 23 and with flange 25 in abutting engagement with the lower end of the body portion 11. The section 21 also includes a downwardly tapering integral portion forming a funnel 26 extending within and projecting downwardly from the ring 22, and provided at its lower smaller end with a juice-draining vent 27. The funnel 26 extends downwardly in the same general direction as the bottom of the tobacco bowl and coacts therewith to provide an annular smoke chamber 28 of relatively large capacity. The drain section 21 is preferably made of bakelite or equivalent hard, non-absorbing material. It is herein suggested that the drain section 21 may be permanently secured to the body portion 11 as by glueing, so that the drain section 21 may be regarded as a fixed part of the bowl holder 10.

A juice-receiving receptacle 29 has an open top internally threaded, and is demountably secured to the lower threaded end of the drain section 21, the threaded end of the receptacle engaging threads 24, and which threads are preferably formed so as to permit the ready mounting, or demounting, of the receptacle relative to the remainder of the pipe when it is desired to empty the receptacle of its accumulated contents. This receptacle is preferably made of bakelite or

- beetleware or equivalent hard, non-absorbing material, and particularly a material which will not retain tobacco odors. It is herein suggested that the holder, including the parts 10 and 21, 5 be formed of aluminum, and it is obviously within the scope of the disclosure to form such holder of one piece of material and where lightness of weight is desired the entire holder may be made of bakelite.
- 10 A gasket 30 is positioned between the abutting ends of the receptacle 29 and drain section 21, and the receptacle is also designed, when threaded into position, to abut the underside of flange 25, and in general the parts are designed so that 15 when the several sections are assembled in their screw-threaded engagements there will be formed, in effect, a solid construction with neatly closed joints between the several sections. Another gasket 31 may be positioned between the 20 bowl 17 and a shoulder 32 formed below the threads 12 on the holder 11.
- 1 A one-piece pipe stem or mouthpiece 33 formed 25 preferably of hard rubber, has one end inserted into the extension 14 and extends entirely therethrough so as to open into the smoke chamber adjacent its upper portion. The pipe stem 33 is twice reduced to form an outer shoulder 34 and an inner shoulder 35. The portion constituting the first reduction between these shoulders is of 30 cylindrical form, as shown at 36, and has a snug but removable fit in the cylindrical portion of the bore in the extension 14. From the shoulder 35 to the inner end 37 of the stem 33 the second reduced portion 38 is slightly tapered, and is designed to engage the small end of the frustoconical portion 16 of the bore to provide a knife edge engagement 39 between the holder and the pipe stem. The portion 38 of the pipe stem is of 35 less external diameter than the internal diameter of the portion of the bore 16 in which it is contained, so as to provide an annular air pocket 40. This knife edge engagement and air pocket provide heat insulating means for minimizing the transference of heat from the more or less hot 40 body portion to the pipe stem 33. The end 37 of the pipe stem projects slightly into the smoke chamber 28 beyond the inner wall of the body portion 11 to provide a drip edge 41 at the end 37, and this construction also tends to prevent the 45 flow of any juice in the smoke chamber from flowing back into the bore 42 of the stem 33 under those conditions where the smoker elevates the bowl above the level of his mouth while smoking.
- It is particularly noted that the bore 42 of the 50 pipe stem while it opens into the smoke chamber is otherwise out of communication with the interior of the receptacle 29, and as a result there is little if any possibility of juices escaping from the receptacle and clogging or passing back through the bore 42.
- It is also noted that the funnel 26 extends into the receptacle 29, with the vent 27 centrally disposed therein but in spaced relation to the outlining walls of the juice-receiving compartment 43 in the receptacle. The compartment extends 55 upwardly about the funnel 26 and thus forms an annular catch basin 44 for retaining the juices within the chamber 43 when the pipe is laid on its side, as indicated in Fig. 2, or when the pipe is inverted in a position upside down from the showing in Fig. 1.
- In operation it will be understood that the pipe 60 is used conventionally, the smoke from the burning tobacco in the bowl 17 is withdrawn through vent 20, smoke chamber 28, and bore 42. Most smoking

tobacco contains tobacco juices, and when used in this pipe flow from the bowl 17 through aligned vents 20 and 27 and into the compartment 43 in the catch receptacle 29. It is also noted that saliva or drip which may accumulate in the bore 42 is permitted to drain therefrom into the smoke chamber and through the vent 27 into the receptacle space 43, as indicated by the arrows in Fig. 1. From this construction it is apparent that moisture and juices are drained out of the smoke 80 conduits and discharged into the lower detachable receptacle from which they may be cleaned from time to time.

It is a feature of this disclosure, that the juices 85 cannot escape out of the receptacle and are retained therein in all positions of the pipe. As noted in Fig. 2, the pipe, even with the receptacle partially filled with juices, can be laid on its side without danger of the juices flowing therefrom back into the other portion of the pipe.

The providing of the pipe stem 33 as a single 90 integral unit permits the use of a construction which can be readily withdrawn from the remaining portion of the pipe to facilitate cleaning, but it is also apparent that the pipe in the form herein illustrated may have its pipe stem cleaned without removing it from the holder, or, if desired, access to the inner end of bore 42 may be provided by unscrewing the tobacco bowl, as will be necessary from time to time in order to thoroughly 95 clean its tobacco receiving compartment.

The knife edge engagement at 39 between the stem and holder at that portion of the holder which is most likely to be hot, provides a construction for bringing the pipe stem in juxtaposition to the hot tobacco bowl 17, and at the same time tends to minimize heat transference to the pipe stem 33. The providing of the air pocket 40 in the projecting extension, which itself is externally air-cooled, tends further to insulate the 100 hot inner end of the extension from the pipe 105 stem, thus further assisting in maintaining the stem cool.

I claim:

1. A tobacco pipe including a wooden holder 110 having a tubular body portion internally threaded at opposite ends and having a stem receiving tubular extension projecting integrally from one side thereof, a tobacco bowl of heat resistant material having a funnel-like lower end, extending into one 115 end of the body portion in threaded engagement therewith and provided at its intruded end with a smoke and moisture-discharging vent, a drain section of bakelite including an outlining ring having 120 opposite ends externally threaded, with an external flange between the threaded ends and with one of the threaded ends in engagement with the other end of the holder, said drain section including a funnel within the ring and coaxing with the tobacco bowl to form a smoke chamber, a hard 125 rubber pipe stem extending entirely through said extension and having its inner end opening into said smoke chamber, a bakelite receptacle having an open end internally threaded and demountably 130 engaging the other end of the drain section ring, said funnel provided at its smaller end with a juice draining vent discharging into the receptacle, and said external flange positioned between the adjacent ends of the tubular body portion and the receptacle and separating the same.

2. A tobacco pipe including a holder having a 135 tubular body portion internally threaded at opposite ends and having a stem receiving tubular extension projecting integrally from one side thereof, a tobacco bowl having a funnel-like 140

- lower end, extending into the upper end of the body portion, in threaded engagement therewith and provided at its intruded end with a smoke and moisture discharge vent, a drain section including an outlining ring having opposite ends externally threaded, with an external flange between the threaded ends and with one of the threaded ends in engagement with the other end of the holder, said drain section including a funnel within the ring and coacting with the tobacco bowl to form a smoke chamber, a pipe stem extending entirely through said extension and having its inner end facing the funnel-like lower end of the tobacco bowl, and opening into said smoke chamber adjacent its upper portion, a receptacle having an open end internally threaded and demountably engaging the other end of the drain section ring, said funnel provided at its smaller end with a juice draining vent discharging into the receptacle, and said external flange positioned between the adjacent ends of the tubular body portion of the receptacle and acting to separate the same.
3. A tobacco pipe formed of four separate sections and comprising in order, from top to bottom, a tobacco bowl, a holder therefor, a drain section and a receptacle, the bowl and drain section being vertically spaced apart to form a smoke chamber therebetween, the lower portion of said tobacco bowl being of conical form opening at its lower end into the smoke chamber and the drain section including a funnel intruded into the receptacle and provided at its lower, smaller end with a vent for draining juices from the smoke chamber into the receptacle, said funnel being spaced from the interior walls of the receptacle to form an annular catch basin to retain the juices when the pipe is laid on its side or inverted, and a pipe stem extending through the holder and having its inner end opening into the smoke chamber and being otherwise free of communication with the receptacle.
4. A tobacco pipe comprising a tobacco bowl, means coacting therewith to form a smoke chamber encircling the lower portion of the bowl, a demountable receptacle for receiving juices discharged from the smoke chamber, said receptacle having a flat bottom forming the bottom of the pipe and having a flat cylindrical compartment of large capacity compared to the smoke chamber, a pipe stem opening into the smoke chamber and otherwise free of communication with the receptacle, said smoke chamber forming means provided with a vent for discharging the juices from the smoke chamber into the receptacle, said vent being positioned within the receptacle, adjacent the bottom and below the top thereof, said space between the vent and the top of the receptacle forming an annular catch basin having a depth greater than the height of the receptacle.
5. A tobacco pipe comprising a holder provided with a tubular extension, a tobacco bowl demountably positioned on the upper end of the holder, a conical shaped funnel coacting with the tobacco bowl to form a smoke chamber above the funnel, a pipe stem extending through the tubular extension and having its inner end opening directly into the smoke chamber above the funnel, and a receptacle into which the lower reduced end of the funnel intrudes and discharges, the discharge end of said funnel being spaced from the bottom and outlining wall of the receptacle to form an annular catch basin about the funnel when the pipe is laid on its side.
6. A cylindrical form of sectional tobacco pipe
- comprising four separable sections and including in descending order, a holder having a tubular body portion and having a tubular extension projecting from one side, a tobacco bowl demountably positioned in the upper end of the body portion and having a conical bottom distending below the bottom of the body portion, a drain section at the lower part of the body portion and including a conical bottom coacting with the conical bottom of the tobacco bowl to form a smoke chamber having a lower conical part and an upper cylindrical part open to the tubular extension and its lower portion open to the tobacco bowl, and a receptacle demountably secured in place to receive juices discharged from the smoke chamber.
7. In a tobacco pipe the combination of a bowl holder including a body portion having a tubular extension projecting from one side thereof, the bore of said extension being cylindrical at its outer end and frusto-conical between said cylindrical part and the interior of the body portion, a one piece pipe stem having one end intruded into the bore of the extension and extending entirely therethrough a portion of said stem having a snug fit in the cylindrical portion of the bore and having the part in the frusto-conical portion of the bore of smaller diameter than said portion to form an annular air pocket about the stem adjacent the end at the body portion of the holder.
8. In a tobacco pipe, the combination of a bowl holder including a body portion having a tubular extension projecting from one side thereof the outer part of the bore through the extension being cylindrical and the inner part of the bore being frusto-conical with its larger end at the inner end of the cylindrical part, a pipe stem extending through the tubular extension into the body portion, the portion of the stem within the frusto-conical part of the bore and adjacent the body portion being spaced from the extension to form an annular air pocket and the portion of the stem in the cylindrical part of the bore providing a plug having a snug fit therein.
9. In a tobacco pipe the combination of a holder comprising a tubular body portion, a tobacco bowl carried thereby and having its lower portion of conical form to coact therewith to form a smoke chamber about the lower portion of the bowl, a one-piece pipe readily demountable stem having its inner end intruded through a side of the tubular body portion and projecting slightly into the smoke chamber above the lower end of the tobacco bowl.
10. In a tobacco pipe the combination of a holder comprising a tubular body portion, a bowl carried thereby to coact therewith to form a smoke chamber about the lower portion of the bowl, a one-piece pipe stem having an end intruded through a side of the body portion and projecting slightly into the smoke chamber, said stem having a circular knife-edge engagement with the body portion to minimize heat transference.
11. In a tobacco pipe the combination of a holder comprising a tubular body portion, a bowl carried thereby to coact therewith to form a smoke chamber about the lower portion of the bowl, a one-piece pipe stem having an end intruded through a side of the body portion and projecting slightly into the smoke chamber, said stem having a circular knife-edge engagement with the body portion to minimize heat transference, and said body part and stem coacting to provide an air pocket encircling the stem to the outside of said knife-edge engagement.

12. In a tobacco pipe, the combination of a holder and a tobacco bowl having its lower portion intruded into the holder, and forming a smoke chamber therebetween, the lower end of the tobacco bowl being conical and provided with a drain vent discharging into the smoke chamber, said smoke chamber being provided above the vent with a smoke outlet, the lower end of the holder being screw threaded, a two-part unit demountably engaging said screw threads and comprising a receptacle for receiving juices discharged from the smoke chamber and a cover for the receptacle, the central portion of the cover being of conical form, and provided at its lower central part with a vent located within and discharging into the receptacle, and said cover forming the bottom of the smoke chamber.
13. In a tobacco pipe provided with a holder having a tubular extension, a stem extending through the bore of the extension and projecting outwardly from the extension, the portion of the stem at the outer end of the extension providing a relatively long snug fit in the extension and the portion of the stem at the inner end of the extension having a knife edge contact with the extension, and the portion of the stem between the long, snug fitting part and the knife edge contacting part being of less diameter than the portion of the bore in which it is contained thereby to form an annular air chamber in the extension at its inner end.
